STOLE

Roslyn W. Salny, Morristown, N. J.

Application July 3, 1952, Serial No. 20,453

Term of patent 14 years

(Cl. D3—3)

To all whom it may concern:

Be it known that I, Roslyn W. Salny, a citizen of the United States, residing at Egbert Hill, Morristown, State of New Jersey, have invented a new, original, and ornamental Design for Stole, of which the following is a specification, reference being had to the accompanying drawing, forming a part thereof.

Fig. 1 is a perspective view of the stole when in use as such.

Fig. 2 is a perspective view showing the outline and shape of the stole.

Fig. 3 is a top plan view of the stole shown in Fig. 2.

Fig. 4 is an end view of the stole shown in Fig. 2.

I claim:

The ornamental design for a stole, as shown.
ROSLYN W. SALNY.
